UNITED STATES PATENT OFFICE.

RALPH T. SENTER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

OMNIBUS TOP.

Application filed May 17, 1924. Serial No. 714,045.

My invention relates to certain improvements in a top, or roof, of an omnibus, or other vehicle, particularly the top of an upper deck of an omnibus.

5 One object of the invention is to provide an open frame, which is arranged to be closed by a curtain that has rollers within a tubular portion of the frame, said tubular portion being located on each side of a central longitudinal aisle.

10 A further object of the invention is to locate the tubular portion of the frame so that it will act as a supporting rail for a person entering or leaving the omnibus.

15 A still further object of the invention is to arrange the individual curtains so that there will be a curtain above each seat that can be manipulated by a passenger or by the conductor, said curtain forming a protecting roof section.

20 In the accompanying drawings:

Fig. 1 is a plan view of one type of omnibus illustrating my invention;

25 Fig. 2 is an enlarged transverse sectional view, showing one-half of the omnibus;

Fig. 3 is a plan view of a portion of the top of an omnibus, showing two of the curtains drawn, the other curtain being rolled and exposing the seat section;

30 Fig. 4 is an enlarged transverse sectional view, illustrating the mechanism in detail;

Fig. 5 is a sectional view on the line 5—5, Fig. 4; and

35 Fig. 6 is a sectional view on the line 6—6, Fig. 4.

Referring to the drawings, 1 is the floor of an upper deck of an omnibus. 2, 2 are the side walls, which enclose the sides of the upper deck. In the side walls are sliding sashes 3, which can be raised or lowered, as desired. Curtains may be substituted for the sash in some instances. The seat structures 4 are preferably arranged transversely, as shown in Fig. 1. The seat structure has 40 cushion sections 5 and a back section 6. A longitudinal central aisle 7, Fig. 1, separates the two series of seat structures.

Extending from the top of the side walls 2 is a series of beams 8, which are shaped, 50 preferably as shown in Fig. 6. These beams have cylindrical ends 9. Extending from one beam to another are tubular longitudinal members 10. These members are held firmly

in the heads 9 by any suitable means. These tubular members 10 are located on each side 55 of the aisle 7, preferably a slight distance back from the inner ends of the seats, as shown in Fig. 2, although they may be located at different points, depending upon the type of omnibus to which my improved top is 60 applied. The posts 11 rest upon the floor 1 in the present instance. The upper ends of these posts are located in sockets 12 in the heads 9.

65 In some cases, it is preferable to provide a post for each head 9, although the roof may be supported at intervals by two or more posts, depending materially upon the length of the omnibus. The beams 8, which are attached to the side walls 2 by brackets 13, or other suitable devices, provide a light, yet rigid open structure that will support the roof curtains, and which have sufficient rigidity to act as a support for passengers when entering or leaving the omnibus. This 70 open roof structure is preferably less in height than the height of the average person standing in the aisle in order that the omnibus may clear any overhead obstructions. The beams are inclined slightly towards the 75 side, as shown, so that the rain water will not collect on the roof.

80 In each tubular section 10 is a roller 14, on which a curtain 15 is wound. This curtain passes through an opening 16 in the cylindrical section 10 and its longitudinal edges are adapted to slide in grooves 17, which are formed by an upper flange 18 on the beam 8 and the sheet metal gutter section 19, which is secured to the lower flange 20 of the beams 8, as shown clearly in Fig. 6, so that any water escaping from the edge of the curtain flows into the gutter and carried to an outlet pipe 21 at the side of the omnibus, as shown clearly in Fig. 4. The 85 roller 14 is an ordinary type of spring roller and has a spring 22, which is shown clearly in Fig. 5.

90 The head 9 is preferably provided with a cap 23, which is secured by screws 24 to the head so that the cap can be detached and the tubular section 10, with the spring roller, removed, when it is necessary to repair the curtain or its roller. Each tubular section has a head 25 at each end in which the 95 spring rollers are mounted. These heads can 100

be removed when it is necessary to withdraw the curtain and its roller from the removable section 10.

While one means of providing access to the spring rollers is shown, other means may be provided without departing from the essential features of the invention. Although the tubular section is in the form of a cylinder, it may be shaped differently without departing from the spirit of the invention, which is to provide a curtain roller support on each side of the aisle. The curtain, when drawn, forms a protecting roof section.

It will be noticed that the curtain is stiffened at intervals by bars 25, which extend into slots 17. At the end of each curtain is a metal strip 26, which, when the curtain is drawn, overlaps the upper edge of the side wall, thereby making the joint rain proof. Within the metal strip 26 is a pinch catch 27, the extremities of which, in the locking position of the catch, extend beyond the longitudinal edges of the curtain and are adapted to extend into an opening in the beams 8, as shown by dotted lines in Fig. 6. This pinch catch can be withdrawn by a passenger, or by the conductor, to release the curtain, thereby permitting it to be rolled within the tubular member 10.

By the construction hereinbefore described, the top of the omnibus is provided with an open frame, which allows a person to stand erect in front of a seat, it only being necessary for a passenger to stoop when passing under the tubular section 10 in going from the aisle to a seat or vice versa. The space above a seat is unobstructed when the curtain is drawn.

When it is desirable, or necessary, to protect passengers occupying the seats, one or more of the curtains can be drawn over the space above the seats. The curtains are made in sections, preferably one section for each seat structure, so that the occupant can draw a curtain over that structure, when desired.

While the curtains are shown spaced so that a curtain will be above each seat structure, they may be of a width greater or less than the space above the seat structure. While the posts are illustrated as extending to the floor, they may be attached to the seat structures without departing from the essential features of the invention.

The invention is especially adapted for the top of an upper deck of an omnibus, but it will be understood that it can be used as a covering for any type of omnibus, or other vehicle.

I claim:

1. The combination in an omnibus, or other vehicle, of sidewalls; a series of transverse seat sections spaced apart to form a central longitudinal aisle; an open top frame consisting of a series of transverse beams connected at their outer ends to the side walls and at their aisle ends by tubular sections; spring rollers mounted in the tubular sections; curtains on the rollers arranged to be drawn towards the sides of the vehicle and to cover the space between two beams; and means for detachably securing said tubular sections to the transverse beams.

2. The combination in an omnibus, of side walls; two series of transverse seat structures spaced apart to form a longitudinal aisle; a series of transverse overhead beams secured to the side walls, each beam having at its inner end a head provided with a detachable cap; longitudinal tubular sections at each side of the central aisle, said sections having their ends mounted in the heads; spring rollers located within the tubular sections; curtains on the rollers, said tubular sections having longitudinal slots through which the curtains can be drawn to close a space between two beams; and means for supporting the roof structure at the aisle ends.

RALPH T. SENTER.
